UNITED STATES PATENT OFFICE.

ANDREW M. NIXON, OF LYNN, MASSACHUSETTS.

VALVE GEAR.

Application filed November 8, 1924. Serial No. 748,538.

This invention relates to valve operation for steam pumps and the like and particularly to direct acting pumps such as feed pumps, in which a steady and positive feed is desired. In pumps of this type it has been supposed necessary to operate by a piston valve, but such pistons being liable to rather rapid wear, soon become leaky and unreliable and cannot be readily repaired without shutting down.

My present invention contemplates an oscillating valve and valve gear by which I am able to get a very positive and reliable operation and which is of a construction so simple as to involve inexpensive installation and great ease in adjustment or repair.

As illustrative of my invention I have shown in the accompanying drawing and will discuss in the following specification an embodiment which is specifically of great utility and which also well illustrates the principles involved by which other modifications and variants of my invention may be designed by others skilled in the art. Throughout the specification and drawings like reference numerals are employed to indicate corresponding parts, and in the drawings:

Fig. 1 is a vertical section through said valve and gear.

Fig. 2 is a face view thereof.

Fig. 3 is a somewhat diagrammatic view of parts of the valve and the gear, and

Fig. 4 is an elevation, partly in section, showing my valve gear applied to a feed pump of conventional type.

In considering my invention in the embodiment shown, the actuating means is the usual positive stroke control. I have shown at 1 a lever operated by a piston P to reciprocate a rod 2, with which it engages between the adjustable nuts 3.

The rod 2 is pivoted at one end midway of the lever 4, which is hung at 4' in a bracket 5. The lever 4 carries an arm 6 formed of a pair of spaced members and having a roller 7 between the ends thereof. The valve case or steam chest 8 covers the two intake ports 9 and 10 of the pump cylinder C

and is provided with an exhaust 11. The ports 9 and 10 are preferably oppositely disposed and are controlled by a pair of valve members 12 on a valve stem 13.

The valve members 12 are set so that one 55 will cover its port, while the other is uncovered, these movements being effected by a slight partial rotation of the stem 13.

The casing 8 is provided with an overhanging bridge or frame member 8¹ in 60 which the stem 13 has bearing. It also affords a bearing 8^a for the end of the connecting link 15 which is attached to the arm 6 and is fitted with a spring 16. The spring 16 is coiled about the link 15 and at 65 one end abuts the bearing 8^a and at its other end is provided with a cap 16^a which abuts a slightly rounded washer 16¹ held on the link 15 by a nut 15¹. The function of this spring is to yieldingly draw the arm 6 70 inwardly towards the valve stem. The valve stem carries near its upper end a cam arm 17 against which the roller 7 bears. As the rod 2 is reciprocated the roller 7 is advanced from the position shown in Figure 2, 75 in which position the upper port 9 is closed and the lower port 10 opened until it arrives over the toe of the cam.

As soon as the roller passes the toe of the cam it is drawn in by the spring 16 so that 80 it lies over the cam in the position indicated in Figure 3, closing the lower port 10 and opening the upper port 9. Upon the return stroke of the rod 2, the arm 6 is drawn downward, its continued motion causing the roller 7 to ride back over the toe of the cam to its original position shown in Fig. 2. The valve is checked at its two positions by check pieces 18, which are cast or attached on the face of the cylinder or other convenient place of mounting. With such gear the piston gets full steam from the beginning to the end of the stroke. There is no dead center to be overcome and 90 the action is positive whether the pump is working fast or slow. The operation is as follows: Steam is admitted from any suitable steam source through the steam inlet 19 into the steam chest 8 and passes through 95 100

one or the other of the ports 9 and 10, depending upon the position of the valve 12, into the cylinder C. In Fig. 3 the port 9 is uncovered and the live steam would therefore pass through said port on top of the piston P and force the piston downwardly. When the piston reaches the extreme limit of its downward stroke, the lever 1 will be actuated, and through the connections 4, 6, 10 and 17 will reverse the position of the valve so as to cover port 9 and uncover port 10, permitting the steam in the pump cylinder to exhaust through port 9 and exhaust port 11, whereupon the live steam within the 15 chest 8 will enter port 10, and the action will be repeated in the reverse direction. The live steam tends to always force valve 12 to its seat so that the valve 12 always covers the exhaust port 11 and prevents the live steam within the steam chest 8 from exhausting through said port, but the valve is a hollow valve so that the exhaust steam from either port 9 or port 10 can pass through the valve into said port.

20 25 The embodiment shown is a simple and satisfactory form and is especially suitable for marine purposes. Various modifications may, however, be made in the design of the valve and the gear, all without departing 30 from the spirit of my invention if within the limits of the appended claim.

What I therefore claim and desire to secure by Letters Patent is:

35 In valve gear for use with a cylinder having a pair of spaced oppositely disposed intake ports and an exhaust port, and a piston reciprocating in said cylinder, a valve casing having an inlet for a fluid under pressure, a hollow valve mounted for oscillation 40 in said casing and constantly seated over said exhaust port by the pressure of the fluid admitted into said casing, said valve having a pair of intake port-blocking faces adapted alternately to cover and uncover 45 said intake ports and so disposed as to each other and as to said intake ports that when one of said intake ports is blocked the other will be uncovered, whereby the pressure fluid may pass into the cylinder through 50 the uncovered port and move the piston in one direction within the cylinder, and motion transmitting connections between said piston and valve comprising a cam arm on the 55 valve stem, a reciprocating arm disposed for movement in the path of the cam arm, a lever for reciprocating said arm, a resilient link for yieldingly holding said reciprocating arm in engaging alignment with said cam arm, and an operating connection from 60 the piston to said lever effective when the piston reaches its limit of travel in said direction to reverse the position of the valve whereby the pressure fluid within the cylinder 65 may exhaust through the now uncovered

intake port and out of the exhaust port of the cylinder and the pressure fluid in the valve casing may enter the cylinder through said now uncovered intake port and actuate the piston in the reverse direction to again reverse the valve.

In testimony whereof I affix my signature.

ANDREW M. NIXON.
